TOY TRAFFIC LIGHT

Grant A. Wiswell, Burlingame, Calif.

Application December 29, 1952, Serial No. 22,902

Term of patent 14 years

(Cl. D34—15)

To all whom it may concern:

Be it known that I, Grant A. Wiswell, a citizen of the United States, residing at Burlingame, State of California, have invented a new, original, and ornamental Design for a Toy Traffic Light, of which the following is a specification, reference being had to the accompanying drawing, forming a part hereof.

Fig. 1 is a front elevational view of a toy traffic light, showing my new design;

Fig. 2 is a side elevational view thereof;

Fig. 3 is a rear elevational view thereof;

Fig. 4 is a top plan view thereof; and

Fig. 5 is a cross-sectional view thereof, taken along the line 5—5 in Fig. 1.

The drawing figures are shaded to indicate color contrast.

I claim:

The ornamental design for a toy traffic light, substantially as shown and described.

GRANT A. WISWELL.
